UNITED STATES PATENT OFFICE.

WILLIAM HENRY THOMPSON, OF LEEDS, COUNTY OF YORK, ENGLAND, AS-SIGNOR TO THE THOMPSON GAS KILN AND OVEN COMPANY, OF NEW YORK, N. Y.

GAS-HEATED BAKER'S OVEN.

SPECIFICATION forming part of Letters Patent No. 341,615, dated May 11, 1886.

Application filed February 24, 1885. Serial No. 156,613. (No model.)

To all whom it may concern:

Be it known that I, WILLIAM HENRY THOMPSON, of Leeds, in the county of York, England, have invented a new and useful Improvement 5 in Gas-Heated Bakers' Ovens, of which the following is a specification.

The object of my invention is to provide an oven in which the heat and products of combustion generated or produced by the use 10 of gas and air in Bunsen or other similar heating-burners will be more effectively and economically applied or utilized in heating the oven.

My invention relates to that class of bakers' 15 ovens in which there are arranged at one side of the baking oven or chamber burner-chambers containing heating-burners of the Bunsen or any other suitable type, and in which the heated products from the burners pass directly through the oven and baking-chamber 20 and escape at the rear end thereof, or the end or side opposite that on which are arranged the burner-chambers.

The invention consists in novel combinations of parts, which are hereinafter described, 25 and pointed out in the claims.

In the accompanying drawings I have represented an oven embodying my invention; and the invention consists in novel features of 30 construction and combinations of parts, which are hereinafter described, and pointed out in the claims.

In the drawings, Figure 1 is a sectional elevation of the oven. Fig. 2 is a horizontal section on the plane of the dotted line $x-x$, Fig. 35 1. Fig. 3 is a transverse vertical section on the plane of the dotted line $y-y$, Figs. 1 and 2, and Fig. 4 is a front elevation of the oven.

Similar letters of reference designate corresponding parts in all the figures.

A designates the baking chamber or oven proper, which is built up of fire-brick and tiles, the bottom being composed of tiles a and the top of tiles a' , supported by angle or 45 T beams a^2 , as shown in Fig. 1. At the front side of the chamber A is the mouth A', closed by a suitable door.

B designates the outside brick-work of the structure, and B' a layer of brick-work above 50 the tile roof a' of the baking-chamber.

The tiles a , which form the bottom of the

baking-chamber, are supported by rows of fire-brick a^3 , and between the rows are metal or earthenware flues or tubes b , the purpose of which will be hereinafter described. Below the courses of fire-brick a^3 , I have shown a concrete bed, C, and below is rubble filling C', as best shown in Fig. 1.

In the front portion of the oven are constructed burner chambers or passages c , which 60 extend transversely across the oven proper or baking-chamber A, as best shown in Figs. 1 and 2. In these chambers or passages c are arranged series of burners d , which are supplied with gas from branch pipes d' , which 65 are provided with suitable valves, d^* , and are connected with a common supply-pipe, d^2 . The burners d are of the Bunsen type, or of any suitable construction to burn gas and air, and the air to supply them enters through 70 passages or flues c , leading from the front of the oven to the chambers c . These flues may be supplied with suitable dampers to regulate the admission of air.

At the back side or rear of the baking-chamber A is a drop-flue, e , with which the baking-chamber is in free communication by an aperture or opening, e' , extending transversely across its rear side, at the top thereof, and from this flue e the tubes or flues b , before referred to, lead forward and enter an escape-flue, f , which extends transversely across under the oven, as shown in Fig. 1 and by dotted lines in Fig. 2, and communicates with the upright smoke stack or chimney f' . If desired, the metallic tubes b might be dispensed with and the communication between the flues e and f be established by flues built in brick, or formed between the supporting-rows of fire-brick a^3 .

I have shown those parts of the structure which form the baking-chamber A as surrounded on the top, sides, and rear back by an envelope or layer, g , of slag-wool or other non-conducting material or substance, whereby the 95 radiation of heat from the baking-chamber will be greatly retarded, and which therefore conduces to the economical operation of the oven.

Leading from the baking-chamber A, at the 100 front thereof, is the usual steam-flue, h , which connects with the chimney f' , and through

which may escape the steam arising from the baking substances. This flue may be controlled by a damper, *h*', operated from the front of the oven, to confine the steam in the oven at the period of the baking when it is desirable.

When the oven is to be heated, the burners *d* are lighted, and the heat and hot products of combustion all pass upward into and through the baking-chamber *A*, from front to rear thereof, and at the rear side pass by the opening *e*' to the flue *e*, from whence they return through the tubes *b* or their equivalent flues below the oven, and to the flue *f*, from which they escape to the chimney. It will therefore be seen that inasmuch as the baking-chamber is internally heated the temperature therein will be raised to a baking-point in the shortest possible time and by the least possible expenditure of gas. When the oven is heated to the temperature desired, the gas is turned off and the baking-chamber is charged with bread or other food, and the use of the oven for baking is continued until the temperature becomes reduced so that it is no longer operative.

I have referred herein only to burners in which is burned a mixture of gas and air; but it is evident that in lieu thereof may be employed burners for using illuminating-gas alone as fuel.

The oven here shown to illustrate my invention is nearly square, as shown in Fig. 2, and hence the result would be substantially the same whether the burner-chambers *c* and outlet opening or aperture *e*' are respectively at or near the front and rear of the chamber, or at the opposite side walls thereof, the flues *e* *b* *f* being of course correspondingly arranged. In an oven in which the baking-chamber is much greater in length from front to rear than in width the best results would be obtained by the arrangement of the burner-chambers at or near the front and the opening *e*' at or near the rear, as the hot products of combustion would have a greater distance to travel through and below the chamber.

I am aware that it is not new in a gas-heated baker's oven which has burner-chambers containing burners arranged at the front of the oven and communicating with the baking-chamber to conduct the hot air and products of combustion through apertures close to the floor of the baking-chamber, at the rear thereof, and thence forward through tubes or flues beneath the floor of the baking-chamber. My combination is distinguished from that above described as old in that the aperture or opening *e*', through which the hot air and products of combustion escape at the rear of the baking-chamber, is at the top of the rear wall and immediately below the top of the oven, said aperture or opening being made in the form of a

long and narrow slot. This difference has an important effect on the operation of the oven. 65

In the oven above referred to as old the colder or cold air which is near the floor of the oven escapes through the apertures or openings at the rear thereof close to the floor, and this air, as it passes forward beneath the floor 70 of the oven, has not sufficient heat to properly heat the floor of the oven. In the class of ovens which are heated by the direct passage of the products of combustion through the baking-chamber no difficulty whatever is experienced in heating the upper part of the baking-chamber; but the difficulty has been to sufficiently heat the floor of the oven, and it is with this object in view that the heated air and products of combustion are passed forward immediately below the floor of the oven. In my oven, instead of the colder air escaping through the apertures at the rear of the oven, the hotter air escapes which is immediately below the top of the oven, and this hotter air 80 is of a temperature to sufficiently and effectively heat the floor of the oven as it passes forward through the tubes or flues beneath the floor.

I have found by practical experiment that 90 it is necessary to have an outlet-aperture for products of combustion, which is at the rear of the oven, immediately below the top thereof, in order that the escaping air and products of combustion shall have sufficient heat to effectively heat the floor of the oven during their forward passage beneath the same.

What I claim as my invention, and desire to secure by Letters Patent, is—

1. The combination, with the baking-chamber *A* and the drop-flue *e*, extending across the chamber *A* at one side thereof, and communicating with the chamber by the horizontally-extending slot *e*', immediately below the top of the chamber, of the burner-chamber *c* and its 100 contained burners, a flue, *f*, extending transversely across beneath the chamber *A*, and tubes or flues *b*, connecting the flues *e* *f*, and extending side by side below the bottom of the chamber *A*, substantially as herein described. 110

2. The combination, with the baking-chamber *A*, having the burner-chambers *c* and their contained burners *d*, extending downward from its bottom, and the opening *e*' at its opposite side, of the transverse flue *f*, below the chamber *A*, the flue *e* at the rear thereof, the rows of fire-brick *a*', for supporting the bottom of the baking-chamber, forming between them parallel channels or spaces, and the tubes *b*, connecting the flues *e* and *f*, and arranged in the 115 channels or spaces between the rows of fire-brick, substantially as herein described.

WILLIAM HENRY THOMPSON.
